UNITED STATES PATENT OFFICE

HENRY P. TAYLOR, OF WINSTON-SALEM, NORTH CAROLINA

CONTAINER FOR MANUFACTURED TOBACCO

Application filed August 2, 1927. Serial No. 210,025.

My invention relates to a container for packing manufactured tobacco and more especially to a container for packing plug and twist tobacco in such a manner as to 5 eliminate the use of end plugs.

My invention has for one of its objects that of packing manufactured tobacco with bottom and top pieces composed of a material whose surface, which is packed next 10 to the tobacco, is embossed or molded to simulate the appearance of portions of leaves of tobacco. I am aware that heretofore many efforts have been made to eliminate the slick appearance of the end plugs in a caddy of 15 boxed tobacco, among which efforts included that of plastering on the heads of the tobacco boxes leaves of tobacco in order that the end plugs may be impressed with this leaf of tobacco in order to give to the outer plugs 20 an appearance which would indicate that they were not end plugs. This method is undesirable in that the finest grade of tobacco, known as wrappers, is necessary, which must be turned over and thrown away 25 when the box is opened, which is a great loss.

It is an object of my invention to pack the plugs of tobacco in a box having end members composed of layers of two different materials, the outer layer being rigid and non- 30 resilient and the inner layer being resilient and fibrous, and the surface of the inner layer being impressed or embossed to simulate the appearance of a leaf or portions of leaves of tobacco, or if desired, the inner 35 portion may be made less resilient or rigid, still having the surface simulating a leaf of tobacco. The outer and inner layers above described may be secured to each other by glue or other materials, thus constituting a 40 head member composed of a homogeneous member, thus eliminating handling.

Another object of my invention is to provide head members for tobacco boxes having resilient inner surfaces on which is impressed 45 the simulation of leaves of tobacco, and will conform to the surface of the plugs of tobacco and impart to the end plugs a natural rough and ready appearance, the natural appearance being secured by having the inner surface of the head member impressed,

embossed, or otherwise designed to simulate the appearance of leaves of tobacco, and the rough and ready appearance being secured by the resiliency of the inner portion of the head member. I am aware that heretofore the 55 head members have been roughened, but this has always resulted in an artificial and unnatural finish to the end plugs of tobacco, due to the fact that the head members were not resilient and could not assume the natural rough and ready finish which is always present on the surfaces of the plugs on the interior of the bulk packed in the box. I am also aware that leaves of tobacco have been used to impart a natural finish to the exterior plugs of tobacco, but this method does not also give the natural rough and ready finish due to the fact that the head members 60 were not resilient.

Some of the objects of my invention having been stated, other objects will appear as the description proceeds, when taken in connection with the accompanying drawings, showing a preferred embodiment of my invention, in which,—

Figure 1 is an elevation of the inner surface of one of the end members, showing the simulations of leaves of tobacco.

Figure 2 is a view partly in cross section of a tobacco box packed full of tobacco employing my end members.

Referring more particularly to the drawings, the numerals 10 and 11 indicate the side wall portions of a box of tobacco. The numerals 12 and 13 indicate two layers of my end members, said end members being secured in position by conventional strips 14, and inside of the box is the bulk of plugs of tobacco, 15. My end members are composed of two layers of material. The outer layer 13 is rigid and non-resilient and is composed of wood, cardboard or other suitable material, while the inside portion 12 is of a composition material such as fibrous vegetable matter, or it can be made of cardboard or other suitable material. The inside portion of the portion 12, which is indicated by the numeral 16 is embossed, stamped or molded to simulate the appearance of portions of leaves of tobacco, wherein one of the stem portions is in-

dicated by numeral 17, and the branch stem portions are indicated by the numeral 18.

It is, of course, to be understood that the layer 12 may be made resilient to assume the contour of the outer surface of the plugs of tobacco, or if desired, it may be made less resilient or rigid and still have its surface, which is placed next to the plugs of tobacco, stamped, embossed or molded to simulate the appearance of portions of leaves of tobacco.

In the drawings and specification I have set forth a preferred embodiment of my invention; and although specific terms are employed, they are used in a generic and descriptive sense only and not for purposes of limitation, the scope of the invention being set forth in the appended claims.

I claim:

1. A head member for tobacco boxes composed of two layers of composition material, the outer layer being rigid and the inner layer being resilient, the surface of the inner layer being adapted to be placed next to the tobacco and being moulded with a reproduction of the surface of a plug of pressed tobacco taken from the interior of a batch of pressed plugs of tobacco.

2. A head member for tobacco boxes composed of two layers of composition material, the outer layer being rigid and the inner layer being resilient, the surface of the inner layer being moulded with a surface, said surface being an actual reproduction of the surface of a plug of pressed tobacco taken from the interior of a batch of pressed plugs of tobacco.

3. A head member for tobacco boxes having the surface thereof, which is adapted to be placed next to the tobacco, composed of resilient material, the entire surface which is adapted to be placed next to the tobacco being moulded with an actual reproduction of the surface of a plug of pressed tobacco taken from the interior of a batch of pressed plugs of tobacco.

In testimony whereof I affix my signature.

HENRY P. TAYLOR.
